[57] CLAIM

The ornamental design for a chocolate having a column
design, as shown and described.

DESCRIPTION

FIG. 1 is a perspective view of a chocolate having a
column design according to my invention;

FIG. 2 is a top plan view thereof;

FIG. 3 is a front elevational view thereof, the rear eleva-
tional view being a mirror image thereof;

FIG. 4 is a left side elevational view thereof, the right
side elevational view being a mirror image thereof; and,
FIG. 5 is a bottom plan view thereof.

FIG. 1

FIG. 2

FIG. 3

FIG. 5

FIG. 4
